UNITED STATES PATENT OFFICE.

JOHN F. O'CONNOR, OF CHICAGO, ILLINOIS, ASSIGNOR TO WILLIAM H. MINER, OF CHAZY, NEW YORK.

ADJUSTABLE SIDE BEARING FOR RAILWAY-CARS.

1,252,295.

Specification of Letters Patent.

Patented Jan. 1, 1918.

Application filed October 23, 1914. Serial No. 868,209.

To all whom it may concern:

Be it known that I, JOHN F. O'CONNOR, a citizen of the United States, residing at Chicago, in the county of Cook and State of

5 Illinois, have invented a certain new and useful Improvement in Adjustable Side Bearings for Railway-Cars, of which the following is a full, clear, concise, and exact description, reference being had to the accompanying drawings, forming a part of this specification.

This invention relates to improvements in adjustable side bearings for railway cars.

The object of the invention is to provide 15 an adjustable side bearing of simple and efficient construction.

In the drawing forming a part of this specification, Figure 1 is an end elevation of 20 a body and truck bolster of a car, showing my improvements in connection therewith. Fig. 2 is an enlarged vertical sectional view taken substantially on the line 2—2 of Fig. 1. Fig. 3 is an enlarged detail sectional view taken substantially on the line 3—3 of Fig. 25 2 and Fig. 4 is a top plan view of the improved adjustable striking plate.

In said drawing, 10 denotes the body bolster and 11 the truck bolster swiveled at the center in the usual manner and provided 30 on each side of the king pin with an adjustable side bearing, each side bearing, as shown, comprising an upper roller member A and an adjustable striking plate B.

The roller member A comprises a supporting bracket 12, having flanges 13 riveted or otherwise secured to the body bolster. Oscillatably mounted in the bracket 12 is a cradle 14 in which is rotatably mounted an anti-friction roller 15, the axis of the latter 40 being at right angles to the pivotal axis of the cradle 14.

The improved adjustable striking plate B, as shown, comprises a base casting 16 having outwardly extended flanges 17 by which it 45 is riveted or otherwise suitably secured to the truck bolster 11. The base casting 16 is of substantially rectangular box-like form, having vertical end walls 18—18 and longitudinally extending side walls 19—19. Within the box-like casting, are mounted 50 three blocks 20 and 21—21, the former having an upper horizontal wall 22, in which is secured a hardened wearing plate 23, adapted to be engaged by the anti-friction roller 55 15. The block 20 also has a vertically ex-

tending side wall 24, which engages one of the walls 19. At each end of the block 20, a pair of spaced webs 25—25 are provided, having inturned flanges 26 at the bottom thereof, the flanges 26 being inclined, as clearly indicated in Fig. 3 and forming with the walls 25 and the inner inclined wall 27, an inclined guideway in which is adjustably 60 slidably mounted a block 28 of substantially triangular construction.

The block 21 has hollow end portions 29, the upper faces of which are inclined or beveled, as indicated at 30, to correspond with the inclined lower faces on the block 20, transversely extending recesses 31 being 70 provided through said hollow end portions 29 to receive bolts 32, the head ends of which are mounted in said triangular shape blocks. The bolts 32 are extended through the wall 19 and each has adjustably mounted thereon 75 a nut 33. The hollow end portions 29 of the block 21 is connected by a longitudinally extending back wall 34 and between this and the adjacent wall 19 of the base casting 16 may be placed one or more shims 35, by 80 which the position of the block 21 can be adjusted inwardly and outwardly, it being apparent that inward and outward adjustment of the block 21 causes a corresponding raising and lowering of the block 20. The 85 parts are held in their adjusted position by tightening the nuts 33 on the bolts 32.

I claim:

1. In a side bearing for railway cars, the combination with a box-like casting adapted 90 to be secured to a bolster, of adjusting blocks mounted within said casting, said blocks having inclined faces, a third block also mounted within said casting and having inclined faces coöperating with the inclined 95 faces of said first named adjusting blocks and provided also with a striking surface, and tightening bolts extending from said adjusting blocks through said third block and adapted to retain all the blocks in adjusted position.

2. A side bearing for railway cars comprising a base casting having an upstanding hollow box-like portion, a pair of blocks adjustably mounted within said box-like portion, one of said blocks being vertically adjustable and the other horizontally adjustable and having coöperating inclined adjusting surfaces, bolts for holding said blocks in adjusted position, provision being made for 110

the insertion of one or more shims between the horizontally adjustable block and a portion of the casting.

3. In a side bearing for railway cars, the combination with a base casting having a hollow box-like portion, of a block horizontally adjustable in said box-like portion, said block being provided with inclined surfaces on its upper face, a second block vertically adjustable in said box-like portion and having also inclined lower surfaces co-operable with the inclined surfaces of the

first named block, the vertically adjustable block being provided with inclined hollow guideways, members adjustably mounted 15 within said hollow guideways and bolts extending from said members through one of the walls of said box-like portion and adapted to retain the members in adjusted position.

JOHN F. O'CONNOR.
